UNITED STATES PATENT OFFICE

STUART PARMELEE MILLER, OF ENGLEWOOD, NEW JERSEY, ASSIGNOR TO THE BARRETT COMPANY, OF NEW YORK, N. Y., A CORPORATION OF NEW JERSEY

DISTILLATION OF TAR OR PITCH TO COKE AND APPARATUS THEREFOR

Application filed August 9, 1929. Serial No. 384,667.

This invention relates to improvements in the distillation of tar or pitch to coke in which the distillation is carried on continuously in a still heated externally while hot coal distillation gases are passed through the still to remove vapors from the distillation of the tar or pitch as they are formed.

According to the present invention, tar or pitch is distilled to coke by direct contact with a current of hot coal distillation gases, and the tar or pitch is also heated by indirect contact with highly heated gases to promote the coking operation. The vapors distilled during the coking operation are swept from the still by the hot coal distillation gases. The presence of the inert gases passing through the still lowers substantially the temperature at which the volatile components of the tar or pitch may be distilled, thus not only avoiding decomposition which would result at higher temperatures, but also increasing the relative rate of removal of the volatile components of the tar or pitch. This aids in the conversion of the tar or pitch to coke, and increases by-product recovery, especially by the rapid removal of the high boiling constituents of the pitch. The hot coal distillation gases enter the still at a temperature at which oils formed from the coal during the distillation are still in vapor form. After leaving the still, these oils, together with constituents volatilized during the coking operation, are condensed from the gases by cooling.

Hot coal distillation gases as they leave the ovens or retorts carry with them fine particles of entrained impurities such as dust, coke, pitch, etc. Such suspended particles as are carried through the coking still will, at least to some extent, be separated from the gases with the oils produced on cooling. However, by subjecting the gases as they leave the coking still and while they are still at a high temperature to a cleaning operation, as by cleaning in an electrical precipitator or in a scrubber, the entrained impurities may be removed from the gases so that on subsequent cooling of the gases clean oils will be obtained.

In order to clean the gases, they may be scrubbed with tar or pitch which may be a

pitch of the same composition as that carried in the gases. The scrubbing may advantageously be accomplished by subjecting the gases to an intense spray of the scrubbing medium. A preferred form of scrubber comprises a chamber in the bottom of which a small body of the scrubbing medium is maintained, and in which a roll adapted to be rotated at high speed is positioned in such a way that it dips but to a slight extent into the body of the scrubbing medium. The roll rotates in such a direction that it throws an intense spray of the scrubbing medium into the gases, scrubbing the gases and thoroughly washing the chamber walls to prevent the accumulation of deposits of pitch or coke thereon.

Where tar is to be distilled to coke, the tar or partially distilled tar may with advantage be employed as the scrubbing medium for removing entrained impurities from the gases leaving the coking still, and the temperatures may be so adjusted that the tar is distilled by the hot gases leaving the still. The partially distilled tar or pitch thus formed will be supplied to the coking still and the vapors and gases from the tar distillation will blend with the vapors and gases from the coking operation, and on subsequent cooling oils which will be clean oil and which will comprise constituents originally present in the tar and pitch and also oils originally present as vapors in the coal distillation gases, will be separated from the gases.

According to this invention, a body of pitch is maintained in a still and a thin layer of the pitch is formed on a moving surface and on exposure to the hot distillation gases passing through the still combined with the application of heat from outside of the still, the pitch is coked and the coke thus produced is continuously removed from the moving surface by a suitable scraping or disintegrating device. The moving surface is advantageously in the form of a drum which dips into the body of pitch maintained within the still. The drum is heated from the inside in any suitable manner, as by passing hot combustion gases through the drum. The process is continuous. Although the gases from a

single coke oven or retort vary considerably in temperature and composition during the coking of a charge of coal, by blending the hot coal distillation gases from a plurality of 5 ovens or retorts, a gas of substantially uniform composition is obtained, and this gas is used for flushing the still.

In the accompanying drawings, the invention is illustrated more particularly as applied to use in connection with a coke oven 10 battery, but it is intended and is to be understood that the invention is not limited thereto, but is applicable also to use in connection with other coal distillation plants.

15 Fig. 1 shows in plan a coke oven battery with a coking still and a tar still in series with the hot coke oven gases passing through the coking still and then through the tar still and the tar after distillation to pitch in the 20 tar still passing to the coke still, countercurrent to the flow of the gases;

Fig. 2 is an elevation of the coking and tar stills;

25 Fig. 3 is a section through the coking still; Fig. 4 is a section through the tar still;

Fig. 5 is a plan view of a modified arrangement in which the gases leaving the coking still are cooled without first being cleaned;

30 Fig. 6 is a section on the line 6—6 of Fig. 5; and

Fig. 7 is a section on the line 7—7 of Fig. 5.

In the drawings, 5 indicates a coke oven 35 battery. The collector main 6 is connected with the individual ovens through uptake pipes 7. A cross over main 8 passes to condensers, etc. (not shown). This apparatus is of the usual type and is shown more or less 40 diagrammatically. At the rear of the ovens is a coking still 9. Uptake pipes 10 from selected ovens pass directly into the coking still. By the proper manipulation of valves in the 45 uptake pipes 10 and the uptake pipes 7, the gases from the selected ovens may be directed either to the collector main 6 or to the coking still 9.

The still may be cylindrical in shape. Within the still is a drum 11 heated by hot 50 gases such as hot combustion gases which enter the drum at 12 and are drawn off from the drum at 13. The drum is slowly rotated, e. g. by means of the gears 19 from any suitable source of power, and in rotating dips into a body of the pitch maintained within the still, and as this pitch is brought up into 55 the atmosphere of the hot coal distillation gases as the drum rotates, the pitch, with the aid of heat supplied from an external source to the interior of the drum, is coked. The hot coke oven gases passing through the still remove vapors from proximity with the pitch almost as soon as they are formed and thus aid in the production of the coke. The rotation of the drum is so timed that the pitch is coked on the drum before being removed.

60 65 When the drum rotates to the position where

it contacts with the scraper 13', coke is removed by the scraper and discharges into the chute 14. A rotating grate 15 controls the rate at which coke is discharged from the bottom of the chute. The coke is quenched in a trough 16 and may be quickly removed from the quenching trough by the belt conveyor 17 before it becomes water soaked.

The hot coal distillation gases leaving the 75 still contain vapors originally present in the gases as they leave the ovens and in addition vapors resulting from the vaporization and decomposition of the pitch within the coking still 9. These hot gases and vapors pass through the main 20 to the tar scrubber and 80 still 21.

Tar is admitted to the still through the pipe 22. This tar is advantageously heated before entering the still. It may be preheated by indirect contact with the hot gases and vapors leaving the still, whereby oils will be condensed from the gases simultaneously with the heating of the tar. A body of tar or partially distilled tar is maintained in the 85 bottom of this still. The still is equipped with a spray device for producing within the still an intense spray of the tarry material which scrubs the gases and cleans them, and at the same time effects distillation of the tarry material by contact with the hot gases.

90 The spraying device shown is the roll 23 which is driven at high speed, for example, 900 to 1200 R. P. M. by the motor 24. This produces an intense spray of tar and pitch in the gases, removing entrained impurities, so-called "tar-fog", etc., from the gases so that the gases leaving the still through the settling tower 25 are free from entrained impurities with the exception of possible particles of the spray carried over from the still by the gases. In order to remove such droplets of pitch spray from the gases, the fresh tar is 95 advantageously fed to the still through the tower 25 and the tower is equipped with baffles 26 over which the tar flows, whereby any entrained drops of tar are washed from the gases and the tar is partially distilled.

100 The gases pass out of the tower into condensing means 26' which may be condensers of the direct or indirect type. Direct condensers are here shown with means for spraying the gases with water or ammonia liquor. The condensate, together with the excess cooling medium, is collected in the decanters 27. From the decanters the clean oil is separately 105 collected in the receivers 28. Beyond the condensers is an exhauster 29 which is provided for drawing the gases and vapors through the system. Means for the recovery of ammonia, light oils, etc. is provided beyond the 110 exhauster.

115 The tar is distilled in the still to produce pitch, which may be a pitch of low melting point or pitch of higher melting point. This 120 pitch is drawn off through the coke trap 30 125

and leveling arm 31 and supplied through the line 32 to the still 9. The depth of tar in the still 21 is controlled by the position of the leveling arm 31, and the depth of tar in this still determines the nature of the spray thrown from the roll 23. Within the still 9 the pitch is further distilled and coked and the coke produced is continuously discharged through the chute 14.

Fig. 5 shows a modified arrangement in which the gases from selected ovens are passed up through the uptake pipes 55 and are collected in the hot gas header 56 and passed through the still 60 which is of the same general type as that described; however, in the still here shown, the coke oven gases pass through the still from one end to the other. The gases and vapors leaving the still are cooled without cleaning and tarry oils 20 separate from the gases. These tarry oils comprise oils originally present in the gases entering the still and oils volatilized within the still, and in addition comprise entrained impurities carried from the ovens by the 25 gases and removed from the gases during the separation of the oils.

The hot coke oven gases enter the still 60 through the main 61, and in passing through the still sweep out the vapors formed and aid 30 in the distillation of the pitch. The pitch is fed to the still through the trough 62 and the seal 63. A body of pitch is maintained in the still, and the drum 65, heated internally by hot gases which enter at 68 and leave at 69, 35 revolves slowly in this body of pitch, and as it revolves exposes a thin layer of the pitch to the action of the hot coke oven gases passing through the still.

Pitch which adheres to the drum as it revolves is distilled and coked by the combined 40 action of the hot gases which pass through the drum in indirect contact with the pitch and give up sensible heat to the pitch, and of the hot coal distillation gases which sweep 45 through the still, removing vapors as they are formed, and increasing the rate at which the volatile constituents of the pitch volatilize.

The drum 65 is revolved at such a rate that the pitch is coked before it reaches the scraper 50 70. The coke removed from the drum collects in the chute 71 and is slowly discharged through the revolving grate 72 into the tank of water 73. The finished coke may be removed from the tank by any suitable means, 55 as, for example, the continuous belt 74. This belt is advantageously so positioned that the coke remains in the water in the tank 73 a sufficiently long time to become thoroughly quenched, but yet is removed before it becomes water soaked.

The hot gases in passing through the still remove the vapors from proximity with the pitch almost immediately as they are formed. 60 This not only hastens the distillation of volatile constituents from the pitch but likewise

by removing vapors from the hot still almost immediately, prevents undue decomposition of the vapors. High oil yields are obtained and the gases and vapors are free from decomposition products which would result if 70 the vapors were maintained at a high temperature over a prolonged period of time. Pitch or partially distilled tar may be distilled in this still. Tar is advantageously 75 partially distilled in other apparatus especially designed for the distillation of thinly fluid tar before being admitted to the still. This may be a still in which the tar is brought into intimate contact with hot coal distillation gases in the form of a fine spray, such 80 as that disclosed in Fig. 1.

The hot enriched gases leaving the still 60 are not clean gases, but may contain particles of pitch, coke, etc., together with the usual tar fog, which were present in the gases as 85 they left the ovens, and which will separate with the oils on cooling to give tarry oils and high boiling resinous distillate. The gases comprise constituents of high boiling range, viz. resins and greases distilled from the pitch 90 in converting it to coke. These high boiling constituents are advantageously separated from the gases in a special hot condenser 95, which may advantageously be an indirect condenser. By passing the gases up through this condenser, semi-solid resinous constituents of high boiling range which separate from the gases in the bottom of the condenser, will be washed down with oils of lower boiling range 100 which will separate in the top of this condenser, and the cooling is preferably so regulated that a sufficient quantity of oils of lower boiling range is separated in the upper portion of the condenser to prevent the condenser 105 becoming choked up with the resinous, semi-solid condensate. This high boiling fraction is separately collected in the tank 76.

The gases pass from the hot condenser to the condensers 77 in which separate tarry oil fractions may be obtained or one total tarry oil may be produced. By spraying the gases 110 with water and cooling them to the ordinary temperature, both heavy and lighter oils may be condensed from the gases and collected in the decanters 78. From the decanters the oil 115 may be readily obtained. An exhauster 79 is shown for drawing the gases through the still and condensers, etc.

Instead of passing the gases directly from the still to the condensers, the gases may first, 120 be passed through cleaning means, such as that described in connection with the preceding figures. On cooling gases which have been cleaned at a sufficiently high temperature, clean oils and resinous products may be obtained directly from the gases instead of tarry products.

I claim:

1. The method of distilling tar to coke 130 which comprises passing hot coal distillation

gases through one still and then through a second still, adding tar to the second still, spraying it in the form of an intense spray into direct and intimate contact with the hot
5 gases in the second still, whereby the gases are cleaned and the tar is distilled, drawing off the residue resulting from this distillation of the tar and adding it to the first still, exposing a film of this distilled tar to the action
10 of the hot coal distillation gases within this first still while simultaneously applying additional heat to the film, whereby the film of partly distilled tar is converted to coke, discharging the coke from the first still, collecting
15 the hot clean enriched gases leaving the second still and cooling them to separate oils therefrom.

2. In combination with coal distillation apparatus, a coking still, means for passing
20 hot coal distillation gases from the coal distillation apparatus to the coking still, a tar still, means for passing the gases and vapors from the coking still into the tar still, means for producing an intense spray of tar in the
25 tar still, coolers for condensing oils from the gases and vapors, means for conveying gases and vapors from the coking still to the coolers, a pitch outlet from the tar still to the coking still, a drum positioned in the coking
30 still on a horizontal axis with means for revolving it at a slow rate of speed, the drum being so situated as to dip into a reservoir for pitch in the still, means for heating the drum internally, a chute for discharging coke
35 from the still and a scraper for removing coke from the drum and adapted to discharge the coke from the still through the chute.

In testimony whereof I affix my signature.

40 STUART PARMELEE MILLER.
